IMPACT PRODUCING IMPLEMENT

Frederick W. Matzie, Los Angeles, Calif.

Application May 9, 1945, Serial No. 592,909

2 Claims. (Cl. 273—80)

1

This invention relates to an impact producing implement, and more particularly to a golf club having a wooden striking head.

The present invention in the broadest aspects thereof is not limited to golf clubs, although such an implement has been selected to illustrate the same.

Golf clubs generally comprise a wooden or steel head applied to one end of a metallic hollow shaft and affixed thereto by means of metal pins or screws. While these tubular metallic shafts possess a reasonable degree of flexibility they do not deform radially to as great a degree as the wooden hosel of a driver club head. The impact of a wooden club head against a ball sets up tension in the hosel due to the extension caused by the concentrated load adjacent the point of attachment between the club head and the shaft. As wood cannot take relatively high tension loads, the tension set up in the hosel at the time of the impact will many times result in failure of the hosel.

A number of means have been devised to reinforce and distribute the load transmitted to the hosel and prevent the same from failing at the time of the impact. One of the most commonly used devices heretofore proposed was the string neck binder which consisted of a tight helically wrapped layer of string over the joint between the hosel of the club head and the tubular shaft. This binder has not eliminated the trouble, for after use the string stretches and becomes loose so that the club head no longer receives support therefrom.

To obviate the difficulties had with the string neck binder, it has been proposed to coat the string with a layer of softened cellulose acetate wound over the string for protection of the same. However, when the acetate dries and hardens the string is pulled away from the club hosel and the shaft, and as a result the club head is not strengthened against the stresses created by the impact when the ball is struck.

The difficulties heretofore experienced with previous shock absorbing devices are obviated by the present invention in that means are provided for placing the hosel of a wooden club head in hoop compression. The hoop compression set up in the hosel should be of such an order that the stresses resulting at the impact will not build up sufficient tension in the hosel to cause the same to fail.

The means for placing the hosel in hoop compression is preferably a sleeve of some suitable resilient material capable of taking the stresses

2

transmitted by the hosel. The sleeve is permanently mounted on the hosel and as the material from which it is formed is resistant to atmospheric corrosion, the sleeve is not likely to fail in use.

To increase the resilience of the sleeve and to distribute the stresses set up in both the hosel and the sleeve, the latter is preferably formed with at least one longitudinally extending slot. The slot terminates in an aperture of a width greater than the width of the slot to prevent the sleeve from rupturing at the inner end of the slot.

To aid in retaining the sleeve on the hosel of the club a ferrule is mounted on the shaft contiguous to the head and prevents the sleeve from moving upwardly relative to the hosel. The ferrule is preferably tapered to fair the jointure between the head and the shaft.

Other features and advantages of the present invention will be apparent from the following description taken in connection with the accompanying drawing in which:

Figure 1 is a fragmentary front elevation of the golf club of the present invention, showing the shaft passing therethrough in dotted lines;

Figure 2 is a sectional view taken longitudinally through the sleeve to show the construction of the slots therein;

Figure 3 is a sectional view taken longitudinally through the ferrule; and

Figure 4 is a cross sectional view taken through the protector, hosel and club shaft.

In the illustrated embodiment of the present invention, referring now to Figure 1, 10 indicates the wooden head of a golf club formed with a striking face and having an elongate neck or hosel 11. The hosel as well as the head proper is formed with a bore for receiving the lower end of a shaft 12.

The end of the shaft received in the bore is held therein by pins 13 formed of some fibrous material fixed in small aligned bores formed in the head and shaft. The fibrous material should be of a strength sufficient to take the loads impressed on the pins but yet sufficiently flexible so as to absorb the shock produced by the impact when the ball is struck by the head. The fiber pins take part of the torsion produced by a badly hit ball and tend to reduce tension in the portion of the hosel taking the thrust of the securing pin at the time of the impact.

Mounted about the upper end of the hosel is a sleeve 14 of some suitable resilient material. The inner diameter of the sleeve should be of

such relative to the outer diameter of the hosel that the wood of the latter will be under compression when the sleeve is forced onto the hosel. As best shown in Figure 2 of the drawing, the sleeve is formed with a plurality of longitudinally extending slots 15, each of which terminates in an aperture 16, preferably circular and of a diameter greater than the width of the slot. These apertures are provided in the sleeve to prevent any tendency of same to rupture at the inner ends of the slots when the sudden shock is applied to the head of the golf club at the time the ball is struck.

Although the sleeve 14 may be formed of any material which is capable of taking the stresses set up therein when the ball is struck by the head, in the now preferred embodiment of the invention the sleeve is formed of a material such as phosphor bronze. The sleeve when formed of this alloy not only possesses the high tensile strength necessary to withstand the tension stresses set up therein, but is sufficiently elastic to take the bending forces produced by the impact at the time the ball is struck. As this alloy is also resistant to corrosion, there is little if any likelihood of the sleeve failing because of corrosive action of the atmosphere.

It will be seen that the sleeve is so mounted to the hosel that the slotted end thereof forms lower portion of the sleeve. The slots increase the resilience of the lower portion of the sleeve and also facilitate mounting of the sleeve about the hosel. As the lower portion of the sleeve is more resilient the forces and stresses transmitted to the sleeve are taken up and distributed throughout the more resilient lower portion of the sleeve. This results in less stress in the hosel adjacent the lower end of the sleeve, and consequently reduces the possibility of failure due to shear in that portion of the hosel.

As the sleeve is resilient it tends to reduce and damp vibrations set up by the impact of the head against the ball particularly when the ball is hit "off center." These vibrations are ordinarily transmitted through the shaft to the hands of the player and result many times in temporary but annoying injury to the players' hands.

The sleeve, as the inner diameter thereof is less than the outer diameter of the hosel, normally holds the wood of the hosel in hoop compression. The compression should be such that the forces created by the impact of the head against the ball will not produce tensional forces greater than the tensile strength of the wood of the hosel. Although the internal force exerted by the shaft against the inner surface of the hosel will tend to place the hosel under tension, the compressive force exerted by the sleeve against the outer surface of the hosel will resist or arrest the force exerted by the shaft to the end that little if any extension of the wood fibers is brought about at the time of the impact. Thus the sleeve in normally holding the wood of the hosel in hoop compression prevents the stresses in the hosel from changing into tension or at least into tensional stresses in excess of the tensile strength of the wood.

To prevent separation of the sleeve 14 from the hosel, a ferrule 17, slipped over the lower end of the shaft before the latter is mounted in the bore of the club head, is fixed to the shaft so that the one end thereof engages the upper end of the sleeve. The ferrule is preferable given a taper to eliminate the shoulder formed by the upper end of the hosel and sleeve. The ferrule thus fairs

the jointure of the head and shaft and enhances the appearance of the club.

The ferrule can be formed of any material which is not subject to atmospheric corrosion. 5 In the now preferred embodiment of the present invention the ferrule is formed by the material "Tenite." This material is not only resistant to atmospheric corrosion but to shock as well. It is easily formed and can be secured in a wide range 10 of colors if desired.

Although the now preferred embodiment of the present invention has been shown and described herein, it is to be understood that the invention is not to be limited thereby for the same is susceptible to changes in form and detail within the 15 scope of the appended claims.

I claim:

1. A golf club comprising a wooden body formed with a substantially flat striking face; an elongate, tapered hosel formed integral with said body and extending upwardly therefrom; a shaft; said hosel being formed with a bore for receiving an end of said shaft; a sleeve having a wall of constant thickness encircling the upper portion 20 of said hosel, said sleeve having a tapered, smooth, inner wall, the angle of taper of said wall being substantially the same as the angle of taper of said hosel, the inner diameter of each portion of said sleeve being less than the initial diameter 25 of the corresponding portion of the encircled hosel so that the wood of that portion of the hosel is held in hoop compression, the lower end of said sleeve being formed with at least one slot longitudinally extending upwardly from the lower edge 30 thereof to a point substantially midway of said sleeve; and a ferrule fixed about said shaft in abutting engagement with said sleeve, said ferrule having an outer diameter at the end contiguous to said sleeve equal to the outer diameter 35 of the latter and an outer diameter at the opposite end slightly in excess of the outer diameter 40 of said shaft.

2. A golf club comprising a wooden body formed with a substantially flat striking face; an elongate, tapered hosel formed integral with said body and extending upwardly therefrom; a shaft; said hosel being formed with a bore for receiving an end of said shaft; a sleeve having a wall of constant thickness encircling the upper portion of 45 said hosel, said sleeve having a tapered, smooth, inner wall, the angle of taper of said wall being substantially the same as the angle of taper of said hosel, the inner diameter of each portion of said sleeve being less than the initial diameter of the corresponding portion of the encircled hosel so that the wood of that portion of the hosel is held in hoop compression; the lower portion of 50 said sleeve being formed with at least one slot whereby said lower portion produces in the wood encircled thereby a lower compressive stress than that produced by the upper portion of said sleeve.
